HEADREST

Robert A. Bobchik, 521 N. Minerva,
Royal Oak, Mich. 48067

Filed June 17, 1965, Ser. No. 85,776

Term of patent 14 years

(Cl. D15—8)

FIGURE 1 is a side elevational view of a headrest illustrating my new design and showing a portion of a seat in phantom for illustrative purposes only;

I claim:

The ornamental design for a headrest, substantially as shown and described.
